BOAT BAILING ATTACHMENT FOR
OUTBOARD MOTORS

Elmer C. Kiekhaefer, Cedarburg, Wis.

Application April 7, 1948, Serial No. 19,606

4 Claims. (Cl. 115—18)

1

This invention relates to the exhaust systems for outboard motors as particularly applied to the bailing of boats and the like.

An object of the invention is to provide a simple, inexpensive boat bailing device which may be connected to an outboard motor for operation therewith.

Another object is to provide a boat bailing device operable in connection with operation of an outboard motor which requires the use of no mechanical operating parts, is easy to install and requires no attention or service.

Another object is to provide a boat bailing device which is automatic during the operation of the boat and requires no adjustments at any time.

These and other objects and advantages of the invention will be more fully set forth in the following description of a preferred embodiment of the invention illustrated in the accompanying drawings.

In the drawings:

Figure 1 is a vertical longitudinal sectional view of the stern of a boat with an outboard motor attached thereto showing the bailing device in side elevation;

Fig. 2 is a detailed view of the drive shaft housing of the outboard motor with parts broken away to show the exhaust chamber therein;

Fig. 3 is an enlarged view partially sectioned similar to Fig. 2 showing an alternative embodiment of the invention;

Fig. 4 is a view similar to Fig. 1 showing the motor in the fully tilted position;

Fig. 5 is a detail section of the check valve shown in Fig. 1;

Fig. 6 is an enlarged vertical longitudinal section of the drive shaft housing supporting the engine of the outboard motor shown in Figs. 1 and 4;

Fig. 7 is a front elevation of the housing shown in Fig. 6;

Fig. 8 is a top plan view of the upper end of the housing shown in Fig. 6;

Fig. 9 is a transverse section taken on line 9—9 of Fig. 6;

Fig. 10 is a transverse section taken on line 10—10 of Fig. 6; and

Fig. 11 is a transverse sectional view taken on line 11—11 of Fig. 6.

The invention is adapted to be employed with outboard motors of the type shown in the drawings having an underwater exhaust outlet and an efficiently operating exhaust system wherein a partial vacuum generally obtains in the expansion chamber of the system during normal operation of the motor.

2

The outboard motor shown in the drawings includes the engine 1 and the hollow drive shaft housing 2 secured beneath engine 1 to receive the engine exhaust and discharge the same through the exhaust outlet 3.

The vertical drive shaft 4 extends from engine 1 within housing 2 to the lower gear housing 5 carrying the propeller 6. The housing 5 carrying the propeller 6 is bolted to the lower end of drive shaft housing 2.

The bracket 7 with screw clamps 8 is provided for removably securing the motor to the transom 9 at the rear end of the boat 10. The swivel bracket 11 is pivoted horizontally at 12 to the clamp bracket 7. The housing 2 is pivoted on a vertical axis to the bracket 11 by means of the hollow swivel pin 13 and the upper and lower lugs 14 and 15, respectively, formed integrally with the housing 2 in the front forward edge thereof to provide for turning of the motor for steering of the boat.

The housing 2 shown in the drawings is similar to that disclosed and claimed in the copending applications of the present inventor for Outboard Motor, filed September 5, 1947, Serial No. 772,344, and for Underwater Exhaust for Outboard Motors, filed January 19, 1949, Serial No. 71,592.

The housing 2 receives the exhaust of engine 1 through openings in its upper end and carries the exhaust downwardly therethrough and rearwardly through exhaust conduit 16 to discharge the same underwater through exhaust orifice 3 into the stream of the propeller. The design of the exhaust system provides an appreciable vacuum within the system for the quiet and efficient operation of the engine.

The invention provides means connected to housing 2 and extending through transom 9 to the bottom of the boat to drain the water from the boat and discharge the same through orifice 3, whereby the boat will be kept dry and substantially free of bilge water at all times.

According to the invention there is illustrated in the drawings a stand pipe 17 having its lower open end near the bottom of the boat and its upper end connected to the fitting 18 secured to and passing through transom 9 a substantial distance above the load water line 19. A flexible conduit 20 connects fitting 18 with a fitting 21 threaded into a hole in the forward edge of housing 2 at a point adjacent the fitting 18. Conduit 20 should be of sufficient length to allow the free turning and tilting movement of the motor on the brackets 7 and 11 and is allowed to hang normally between the motor and boat, as shown.

The location of fitting 18 in transom 9 should be as far above the water line 19 as possible for safety. However, the fitting should not be higher from the bottom of the boat than the normal vacuum of housing 4 can lift the water from the bottom of the boat.

Preferably one end of conduit 20 should be readily detachable from fitting 18 or 21 so as not to interfere with the removal of the motor from the boat.

An alternative means for connecting conduit 20 and housing 2 may be provided as shown in Fig. 3.

In this embodiment the fitting 22 is employed to connect the conduit 20 with the lower end of the hollow swivel pin 13 extending from bracket 11 through the lower lug 15. The drilled passageway 23 in housing 2 registers with the slot 24 in pin 13 to provide communication between conduit 20 and the housing.

If desired, should the construction of the exhaust system provide an insufficient vacuum for removal of bilge water for a given height of standpipe 17 at times during the operation of the motor, a check valve 25 may be employed at any suitable point between the mouth of standpipe 17 and the housing 2 to prevent exhaust from forcing its way into the boat. Where the check valve 25 is located in the standpipe or fitting 18, it additionally prevents water from entering the boat under emergency conditions when being operated without the connection of conduit 20 to housing 2. Drive shaft housing 2 which provides an exhaust system of sufficient vacuum for removal of bilge water comprises a hollow aluminum casting having generally uniform wall thicknesses so that the interior section of the housing, as will be described, corresponds generally to the outer body of the housing. The lugs 14 and 15 extending forwardly of the housing and formed integrally therewith receive the upper and lower ends of the swivel pin 13 carried by bracket 11 for the pivotal support of the motor as described for steering of the boat.

The upper end of the housing 2 is of general dimensions substantially equal to the corresponding dimensions of the engine crankcase 26 and cylinder block 27 of engine 1 to fully support the same, and is provided with an opening 28 registering with the lower open end of exhaust chamber 29 of the engine block to receive the exhaust gases therefrom. Bolts or other suitable means secure the engine 1 in place on the housing.

The discharge port 30 in the engine block 27 opens from the water circulating system of the engine and registers with the opening 31 in the housing to discharge the water into the upper end of the housing.

The exhaust outlet 3 is provided with the discharge opening or orifice 32 and is located at the lower end of the housing beneath and rearwardly of the propeller anti-cavitation plate 33 to discharge the exhaust gases with the cooling water into the vortex of the propeller.

The upper end of the housing provides a chamber of substantial size immediate to exhaust chamber 29 and in the embodiment of the invention shown in the drawings is further enlarged to extend rearwardly of the engine as at 34. The forward vertical edge of the housing is preferably straight for the entire length thereof. The cross-section of the housing moving downwardly from the upper end becomes immediately substantially more narrow and stream-

lined relative to the direction of movement of the housing through the water and diminishes proportionately to a short distance above the waterline 19 of the housing.

5 The underwater part of the housing below waterline 19 extends a substantial distance rearwardly to the rear edge of plate 33 and is of particularly narrow dimensions for maximum streamlining and reduced frontal area. The lower end piece which forms the discharge outlet 10 3 having the opening 32 is formed integrally with the body of the housing and should be as narrow as possible within the limitations of the inner 15 dimensional requirements, as will be described, so that there is no increased drag of that part of the housing. The threaded opening 35 beneath lug 15 of housing 2 is adapted to receive fitting 21 and is located adjacent to transom 9 of the boat to require conduit 20 to be of minimum 20 length.

Housing 4 provides an exhaust passage for the gases from the engine to the underwater discharge opening of substantially uniformly decreasing cross-section. The cooling of the exhaust 25 gases is effectively provided for by the large water-cooled surface areas of the housing particularly at the upper end thereof so that the exhaust gases immediately upon entering the housing begin a contraction which is substantially uniformly continued during passage through the housing and until discharge into the stream of the propeller. The uniform contraction of the gases provides a substantially uniformly increasing velocity of flow through the 30 housing whereby the normal vacuum conditions obtained at the lower end thereof is extended with maximum effect up into the housing.

The exhaust gases are substantially uniformly and continuously accelerated in flow from the 40 upper end of the drive shaft housing until they are discharged through opening 32 at the bottom. By reason of this fact the gases are drawn from the engine block rapidly so that the scavenging of the engine is more perfect and there is an increase in engine efficiency. In this 45 respect the present invention differs greatly from former exhaust systems wherein the gases were often interrupted in flow and were accelerated in a non-uniform and, in fact, non-continuous manner so that the engine received very little, if any, of the advantage obtainable with the underwater discharge.

The substantial and gradual reduction in cross-sectional area of the drive shaft housing 55 from top to bottom provides for an increase in velocity of the gases, and utilizes the contraction of the gases on cooling to effect the final acceleration in the flow of the gases.

The contraction of the gases and the effect of 60 the propeller slip stream past outlet 3 effects a negative pressure within housing 2 which materially increases the performance of the engine and which may be utilized as a pump to effect the bailing of the boat.

65 The invention provides an inexpensive bilge pump for use with small outboard motor boats which is simple and efficient. The pipe and flexible conduit may be large enough to effect a quick bailing of small amounts of bilge water, but should not be so large as to appreciably effect the functioning of the engine exhaust when allowing air to pass into the exhaust.

70 Various embodiments of the invention may be employed within the scope of the accompanying 75 claims.

I claim:

1. In an outboard motor adapted to be secured to the transom of a boat, the combination comprising an engine, a housing supporting said engine, a propeller carried by said housing, an exhaust chamber in said housing to receive exhaust gases directly from said engine and having an underwater exhaust opening rearwardly of and adjacent said propeller whereby said chamber in the normal operation of said engine is subject to substantially less than atmospheric pressure, a conduit having one end open at the bottom of the boat and communicating with said chamber, said conduit being adapted to extend and permitting the motor to be freely pivoted for steering and for raising from the water.

2. In a dirigible outboard motor including a bracket adapted to be secured to the transom of a boat, the combination comprising an engine, a housing pivotally supported by said bracket for steering, a propeller carried by said housing, an exhaust chamber in said housing to receive exhaust gases from said engine and having an underwater exhaust opening rearwardly of and adjacent said propeller, said chamber in the normal operation of said engine being subject to substantially less than atmospheric pressure, and a conduit from said housing adapted to extend to the bottom of the boat for automatically bailing the latter by the suction in said chamber.

3. In an outboard motor including a bracket adapted to be secured to the transom of a boat, the combination comprising an engine, a housing supporting said engine and pivotally supported by said bracket for steering, a propeller carried by said housing, an exhaust chamber in said housing to receive exhaust gases from said engine and having an underwater exhaust opening rearwardly of and adjacent said propeller whereby said chamber in the normal operation of said engine is subject to substantially less than atmospheric pressure, a pipe having one end

5

open at the bottom of the boat, a conduit fitting connected to the other end of said pipe and adapted to pass through the transom of the boat substantially above the load waterline thereof, and means connecting said pipe and fitting to said chamber and permitting the motor to be freely pivoted for steering and for raising from the water.

4. In an outboard motor adapted to be secured to the transom of a boat, the combination comprising an engine, a housing, a propeller carried beneath said housing, an exhaust chamber in said housing to receive exhaust gases from said engine and having an underwater exhaust opening rearwardly of and adjacent said propeller whereby said chamber in the normal operation of said engine is subject to substantially less than atmospheric pressure, a vertical pivot pin passing through lugs formed integrally with said housing and secured by means of a bracket to the transom of the boat to support the motor, a passageway from said chamber to the lower end of said pin, and a conduit connected to the lower end of said pin and adapted for passing through the transom to the bottom of the boat for automatically bailing the latter by the suction in said chamber.
